DESIGN FOR AN INTERCOMMUNICATING SYSTEM STATION UNIT

Martin Wasserman, Racine, Wis., assignor to Webster Electric Company, Racine, Wis., a corporation of Delaware

Application October 18, 1947, Serial No. 141,993

Term of patent 14 years

(Cl. D26—14)

To all whom it may concern:

Be it known that I, Martin Wasserman, a citizen of the United States, residing at Racine, in the county of Racine and State of Wisconsin, have invented a new, original, and ornamental Design for an Intercommunicating System Station Unit, of which the following is a specification, reference being had to the accompanying drawings, forming part thereof.

Fig. 1 is a front elevational view of an intercommunicating system station unit embodying my new design;

Fig. 2 is an end elevational view thereof; and
Fig. 3 is a top plan view thereof.

The characterizing features of my new design are shown in full lines in the drawing.

I claim:

The ornamental design for an intercommunicating system station unit, substantially as shown and described.

MARTIN WASSERMAN.
